UNITED STATES PATENT OFFICE.

DAVID H. SAUNDERS, OF GLOUCESTER, MASSACHUSETTS, ASSIGNOR TO HANNA V. P. MERCHANT AND AUGUSTA T. SAUNDERS, OF GLOUCESTER, MASSACHUSETTS.

PRINTING-PRESS.

SPECIFICATION forming part of Letters Patent No. 757,967, dated April 19, 1904.

Application filed January 15, 1903. Serial No. 139,117. (No model.)

To all whom it may concern:

Be it known that I, DAVID H. SAUNDERS, a citizen of the United States, residing at Gloucester, in the county of Essex and State 5 of Massachusetts, have invented certain new and useful Improvements in Printing-Presses; and I do hereby declare the following to be a full, clear, and exact description of the invention, such as will enable others skilled in the art 10 to which it appertains to make and use the same.

The present invention relates to printing-presses, and more particularly to presses of the job-printing type. In presses of this character there is a fixed type-bed and a moving platen for carrying the sheet of paper to be printed into contact with the type. As a means of placing ink upon the type it is customary to employ a number of rollers arranged 15 in series, which rollers are carried over a disk or table upon which the ink has been placed, covering their surfaces with ink and transferring it to the bed of type over which the rollers are subsequently moved.

In the production of high-grade work, such as half-tones and other matter printed from plates, it has been found necessary to "double roll" the plate for each impression taken, for the reason that a single operation of the rollers has been insufficient to uniformly ink the 20 whole surface of the plate, since the ink on any given roller becomes practically exhausted after a complete rotation of the roller over the surface to be inked, and it is impracticable to use rollers of large diameters. The result of such a single-rolling process is streaked and uneven surfaces where the length of the plate is greater than the circumference of a roller. Many expedients, among them 25 being a pyramidal arrangement of rollers, have heretofore been suggested and tried, but without successfully attaining the end sought.

Because it has been necessary in the class of work described to move the inking-rollers 30 through two complete cycles as often as an impression is made the lives of these rollers have been short and the time consumed very great.

The object of the present invention consists in improved means whereby in high-grade work the plate may be inked by a single rolling.

A further object consists in adjusting means whereby the tension on some of the inking-rollers may be varied.

Further objects of the present invention will appear in connection with the following description.

The present invention is illustrated in the accompanying drawings, in which—

Figure 1 shows a side elevation of my improved press, some of the ordinary attachments being omitted for the sake of clearness. Fig. 2 is a section of the machine, taken at right angles to the main shaft, the ink-disk 65 being omitted and the rollers being shown diagrammatically. Fig. 3 is a front elevation looking at the machine from the right-hand side of Fig. 1. Fig. 4 is a rear elevation, the ink-disk being removed. Figs. 5 and 6 show 70 portions of the inking-rollers employed, Fig. 6 being a modification. Fig. 7 is a cross-section through one of the rollers. Fig. 8 is a detail view illustrating the carriage in which are mounted the pyramid of inking-rollers. 75

Similar reference characters will be used to denote like parts throughout the specification and drawings.

A represents the frame of the machine, and this may be of the same type as those now in 80 use, except as the improvements constituting the present invention necessitate alterations.

B is the driving-shaft, provided with the usual pulleys B' and B² at one end thereof and the fly-wheel B³ at its opposite end. Motion is transmitted from the shaft B to a pair of large gears C' by means of a pair of small pinions B⁴, which are mounted on the shaft 85 and which mesh with said gear-wheels.

Each gear-wheel C' is provided with a centrally-projecting shaft or hub C, which is journaled in the frame of the machine, the free ends of these hubs projecting slightly through the frame in order to support the roller-wings to be hereinafter described. A 90 stiffening-boss C² extends radially on the inner 95

face of each gear-wheel, and a shaft C³ extends between the gears and has its ends secured thereto near the outer ends of the bosses C². The shaft C³, in connection with the 5 gear-wheels C', forms a crank which transmits motion to the inking-rollers and platen.

D is the platen, which may be of any preferred form and is pivotally mounted at D' upon the frame of the machine.

10 The mechanism for operating the platen will now be described.

A massive lever E is pivoted to the frame of the machine at E'. A pair of links E² connect the crank-shaft C³ to this lever, so that

15 when the crank revolves the lever is oscillated about its pivot. The lever E is connected with the platen D by means of links E³ E³ and E⁴ E⁴, the links E³ E³ being pivoted at one end to the lever E and supported at the other

20 end upon a shaft E⁵. This shaft E⁵ serves also to support one end of each of the links E⁴ E⁴, which are pivotally secured to the platen. A pair of struts E⁶ are mounted at their one end upon the shaft E⁵, while at their

25 other end they are provided with concave bearing-seats fitting against bosses A⁶ on the frame of the machine and concentric with the shafts or hubs C. A pair of collars e⁶ e⁶, secured to each of said struts, surround the ends 30 of said bosses, which project laterally from the frame. The thrust of the struts is therefore taken by a practically solid mass of metal, including the bosses A⁶ and the hubs C. The links E³ E³ are short as compared with the

35 links E⁴ E⁴, and the struts E⁶ determine the path of movement of the shaft E⁵—namely, in the path of a circle having the axis of shafts C for a center. This construction, in connection with the manner of mounting the lever E, en- 40 ables the lever to exert what may be termed a “constant” pull, the links E³ being always practically tangent to the arc through which the pivotal connection with the lever E moves and the angle between the struts E⁶ and links

45 E³ varying but slightly. The relatively great mass of the lever E serves to effectually counterbalance the heavy platen, and it has been found in practice that at a much higher rate of speed than has heretofore been attainable 50 the smoothness of action is not impaired.

Fig. 2 shows the parts in the position in which the platen is at the outer end of its stroke. It will be seen that during the first portion of the rotation of the crank C² the lever E remains practically stationary, this permitting the operator to remove the printed sheet and replace it by another. As the crank continues to revolve, however, the line of force between it and the lever changes from the initial direction, parallel with the lever, to a substantially perpendicular direction, causing a great angular velocity of the lever. After rotating nearly one hundred and eighty degrees the crank-shaft again moves approximately 65 parallel to the lever, the platen being slowly

and powerfully pressed against the type. The release of the platen is slow at first and then rapid, until the crank has almost completed its cycle, when the platen again moves very slowly. A great saving of time is accomplished by means of this manner of moving the platen, since the platen moves at a high rate of speed during practically the whole of its return stroke, there being no necessity for a slowing down except for a short distance at 75 each end. At the beginning of its primary stroke the movement is retarded for a greater distance, enabling the operator to remove a sheet and replace it by another.

The links E⁴ and struts E⁶ are substantially 80 parallel when the platen is in proximity to the type-bed, while the links E⁴ are substantially perpendicular thereto. The principal stresses are therefore borne by the links E⁴, struts E⁶, and shaft E⁵.

85 The present invention resides in the inking apparatus herein illustrated.

For ordinary purposes a single layer of inking-rollers answers very well; but for high-grade work such an arrangement necessitates 90 at least a double rolling to secure even effects. It has been proposed to use a pyramid of rollers—two, which will hereinafter be referred to as “form-rollers, in contact with the surface operated upon, and a third, which will 95 hereinafter be referred to as a “distributing-roller,” frictionally engaging these two. Such an expedient failed, however, to give good results, since it was found that not enough friction could be developed to turn all three 100 rolls; but, instead of revolving, they would slip. If a great tension was placed upon the rolls, the slipping was not obviated; but the rollers were torn and destroyed.

The present invention comprehends means 105 for rendering the use of the pyramidal arrangement practicable, and this is accomplished by causing the lower rolls to be positively driven as they are reciprocated.

A pair of roller-wings F are supported upon 110 the outer ends C⁴ of the hubs or shafts C, there being one wing on each side of the frame. These wings are each provided with a series of spring-pressed rods carrying the inking-rollers. In the form of my invention 115 illustrated I employ five of these rods f', f'', f³, f⁴, and f⁵, though of course any desired number may be adopted, and the arrangements of the springs may be varied. The two outer rods carry ordinary rollers F' and F'', 120 respectively, while the inner group of three rods is joined together and serves to yieldingly support the carriage, in which are mounted the three rollers forming the pyramid. There are two of these carriages, one 125 for each wing, and are designated by G. Fig. 8 shows in detail one of these carriages with the rollers in place. The carriage G consists of a lower frame or saddle G' and a detachable cap G², pivoted thereto at G³. The frame 130

G' is provided with downwardly-opening bearings g and g' for receiving the axles of the form-rollers F³ and F⁴. The cap G² also contains an open-ended bearing g^2 , serving to retain in place the screw-shaft F¹⁰ of the upper distributing-roller F⁵. The free end of the cap G² is secured by means of a screw G⁴, swiveled to the frame G' at G⁵ and extending through a slot in the arm G⁶ of the cap. A thumb-nut G⁷, threaded upon the swivel-screw and engaging the arm G⁶, effectually locks the parts together. This construction provides a means for removing all the rollers from the carriage in an expeditious manner, for it is necessary to merely loosen the thumb-nut, whereupon the cap may be swung back and the upper roller taken out, while the carriages may be bodily lifted from the lower rolls. It is of course unnecessary to employ a carriage having a hinged cap at each end of the rollers, since in one of the carriages the saddle and cap may be integral. As a means for adjusting the pressure between the rollers F³, F⁴, and F⁵ I have provided a set-screw G⁸, threaded through a boss G⁹ in the carriage-cap and bearing upon the screw-threaded shaft F¹⁰, upon which the roller F⁵ is supported. A lock-nut G¹⁰ holds the screw G⁸ in its adjusted positions. The carriage G is secured to the wing F by means of a pin g^4 , passing through openings g^3 in the carriage-frame, and a registering-opening in the upper end of the rod f³.

It will be seen that by tightening the set-screw G⁸ the tendency will be to lift the carriage against the tension of the three intermediate springs of the wing, thereby forcing the distributing-roller F⁵ against the supporting form-rollers F³ and F⁴. This is a very important feature of my improved inking mechanism, inasmuch as the roller F⁵ may be permitted to bear upon the rollers F³ and F⁴ with a pressure due to its own weight only, or, if desired, the set-screw may be so adjusted as to bring the entire tension of the three intermediate springs to press the roller F⁵ against its supporting-rollers. When thin inks are employed, it is of course obvious that the pressure between the three rollers should be small, while with thick inks considerable pressure is desirable. The pressures at opposite ends of the rollers may be adjusted independently of each other. As was stated previously, this pyramidal arrangement of rollers has not been a success heretofore; but I have found that by giving the lower are formed rollers F³ and F⁴ a positive rotary movement as they are advanced the obstacles preventing the use of such arrangement are overcome. This result may be accomplished in several ways, either by frictional engagement of an adequate character or else by means of a toothed connection between the rollers and supporting-ways. In the preferred form of my invention frictional engagement is employed.

The rollers F', F², F³, and F⁴ consist, preferably, of a shaft F³⁰, carrying a cylinder F³¹ of the composition usually employed for inking-rollers, the part F³¹ being of a length sufficient to extend entirely across the bed. Splined to each end of this shaft is a truck F³², the trucks running upon ways A' and A², provided therefor adjacent the bed.

In Figs. 5 and 7 I have shown the roller-trucks as being provided with grooves f⁶, extending circumferentially thereof.

In Fig. 5 the walls f⁷ and f⁸ of the grooves converge to a point, while the projection formed by adjacent grooves is flattened, as at f⁹. The ways A' and A², upon which the ends of the rollers run, are likewise grooved, as at a, the surfaces a', a², and a³ corresponding to the surfaces f⁷, f⁸, and f⁹ on the rollers. In Fig. 7 the grooves f⁶ are shown as ending in a channel f¹⁰ in order to prevent "bottoming" of the component parts. In this construction the rollers and ways are in engagement only throughout the inclined walls of the grooves, so that the greater the pressure upon the rollers the greater will be the wedging action and resulting resistance to the passage of the rollers. As the rollers are moved along these ways, therefore, they are given a positive rotary movement, and the three rollers F³, F⁴, and F⁵ will be tied together, as it were, giving the effect of one large roller of a circumference equal substantially to that of the three.

The distributing-roller F⁵ comprises, preferably, a hollow cylinder of steel or other metal screw-threaded upon its shaft F¹⁰, whereby as the carriage moves and the lower rollers revolve and the roller F⁵ is frictionally driven therefrom it is given also an axial movement, causing a more uniform distribution of the ink. Besides causing a positive rotary movement to be given to the inking-rollers the intermeshing parts on the roller-trucks and the ways hold the lower rollers against lateral or axial movements, which would otherwise be very apt to occur, because of the axial movement imparted to the upper roller through said lower rollers.

In Fig. 6 I have shown a modification in which the rollers are provided with gear-teeth F²⁰, the ways A' and A² being in that case also provided with teeth. The wings F are operated by means of connections with the crank-shaft C³. A pair of links F¹¹ connect the crank-shaft C³ with levers F¹², mounted in the frame of the machine. A shaft F¹⁴ unites the levers F¹² and carries at its ends a pair of links F¹⁵, which are pivoted to arms F¹⁶, projecting from the wings F. As the shaft B revolves its motion is converted into an oscillatory movement of the platen and of the wings.

It is thought that the operation of the various parts has been sufficiently set forth in con-

nexion with the preceding description, and no further exposition thereof is deemed necessary.

The platen and the inking-rollers are both 5 operated from the same crank-shaft, thereby lessening the number of parts required.

The inking mechanism reduces by one-half the time necessary to ink the form in high-grade work and the number of strokes necessary therefor, the life of the rollers being prolonged and more uniformity being secured.

The superimposing of the metallic distributing-roller above and between the lower composition form-rollers obviates a difficulty 15 which has heretofore been experienced in the inking mechanism on presses of the job-printing type. The composition rollers during the operation of the machine become warm and soften or "melt," as it is termed, permitting a flattening of the rollers, this being augmented by the tension on the rollers. In the common arrangement of rollers heretofore employed this "melting" has been frequently sufficient to cause adjacent rollers to contact 20 with and to adhere to each other, causing pieces to be torn from the surfaces thereof. In my arrangement the metallic roller separates the composition rollers and prevents such contact and consequent damage.

Having described my invention, I claim as new and desire to protect by Letters Patent of the United States—

1. A printing-press having in combination,

form-rollers, means for moving said rollers bodily over the form, means for positively rotating said rollers, and a distributing-roller resting upon and frictionally driven by said form-rollers, substantially as described. 35

2. A printing-press having in combination, a fixed bed, grooved ways adjacent said bed, 40 form-rollers provided with ribs for engaging said grooved ways, a distributing-roller resting upon and frictionally driven from said form-rollers, and means for moving said rollers across the bed, substantially as described. 45

3. A printing-press having in combination, form-rollers and a distributing-roller arranged above and between said form-rollers, a spring-held support for said rollers, means for subjecting the distributing-roller to the 50 full tension of said spring or to any part thereof, and means for positively rotating said form-rollers, substantially as described.

4. A printing-press having in combination, form-rollers and a distributing-roller arranged above and between said form-rollers, a spring-held support for said rollers and means for subjecting the distributing-roller to the full tension of the spring or to any part of such tension, substantially as described. 55 60

In testimony whereof I affix my signature in presence of two witnesses.

DAVID H. SAUNDERS.
